Primary Examiner — Samantha Wood(74) *Attorney, Agent, or Firm* — Fitch, Even, Tabin & Flannery, LLP(57) **CLAIM**

The ornamental design for a sensor support, as shown and described.

DESCRIPTION

- 1.1** : Front
1.2 : Side
1.3 : Top
1.4 : Bottom
1.5 : Back
1.6 : Perspective top
1.7 : Perspective bottom

The portion of the design shown in the color black is for the purpose of illustrating portions of the sensor support and forms no part of the claimed design. The broken lines shown in the disclosure depict portions of the sensor support that form no part of the claimed design.

1 Claim, 7 Drawing Sheets(56)
